UNITED STATES PATENT OFFICE

143,547

DESIGN FOR A HYDRAULIC PUMP AND CONTROL UNIT

Harvey W. Rockwell, Cedar Rapids, Iowa, assignor to La Plant-Choate Mfg. Co. Inc., Cedar Rapids, Iowa, a corporation of Delaware

Application February 12, 1945, Serial No. 117,901

Term of patent 7 years

(Cl. D65—1)

To all whom it may concern:

Be it known that I, Harvey W. Rockwell, a citizen of the United States, residing at Cedar Rapids, in the county of Linn and State of Iowa, have invented a new, original, and ornamental Design for a Hydraulic Pump and Control Unit, of which the following is a specification, reference being had to the accompanying drawings, forming a part thereof.

Fig. 1 is a front elevational view of a hydraulic

pump and control unit embodying my new design;

Fig. 2 is a perspective view taken from the right-hand front corner of Fig. 1;

Fig. 3 is a rear elevational view thereof; and

Fig. 4 is a perspective view taken from the left-hand front corner of Fig. 1.

I claim:

The ornamental design for a hydraulic pump and control unit, substantially as shown.

HARVEY W. ROCKWELL.
